MEANS FOR SHARPENING BITS

Filed July 10, 1939

FIG. 1.

UNITED STATES PATENT OFFICE

2,298,018

MEANS FOR SHARPENING BITS

William J. Moerlin and Robert C. Berggren,
Denver, Colo., assignors to The Mine and
Smelter Supply Company, Denver, Colo., a cor-
poration of Colorado

Application July 10, 1939, Serial No. 283,579

6 Claims. (Cl. 90—11)

This invention relates to improved method and means for maintaining detachable rock drill bits or the like in optimum operating condition.

As is very well known to those skilled in the art, detachable rock drill bits are being quite extensively used in the mining industry and in other industries where rock drilling is practiced. When the drill bits are used, they are removably attached to an operating shank or rod, usually by a threaded socket in the bit being engaged by a similarly threaded end on the shank or rod.

Such bits ordinarily have a plurality of radial cutting edges, and as they are used, these edges become dull and require sharpening. Such detachable bits are usually of a general frusto-conical shape, the cutting edges being positioned radially at the large end and the socketed connection at the smaller end. If these cutting edges are sharpened by removing metal therefrom, as is the common practice, the bit tends to lose its original cutting diameter or gage, which is objectionable. Therefore, it is highly desirable to maintain cutting diameter or gage on such a bit.

An excellent way to sharpen detachable rock bits of this character is to heat them red hot and mill them with a specially designed milling cutter while they are in this heated condition. Handling such heated bits for so sharpening them, presents certain difficulties.

Therefore, it is an object of the present invention to provide an improved method and means for sharpening detachable rock drill bits and maintaining their cutting diameter or gage.

Another object is to provide such a method and means that may be used quickly and conveniently by an operator to so recondition such a bit.

A further object is to provide an improved method and means for handling and reconditioning heated detachable rock drill bits or the like, that may be kept in constant operation without overheating said means.

Still another object is to provide in such a method and apparatus, means for moving a hot detachable bit or the like, from a sharpening position to a gage-cutting position in one prompt, continuous operation.

A still further object is to provide means for rotating a hot bit adjacent a gage-cutter.

Other objects and advantages reside in details of design and construction which will be more fully disclosed in the following description and in the drawing wherein like parts have been similarly designated and in which:

Figure 1 illustrates a front elevation partially in section corresponding to line 1—1 of Figure 2, of apparatus embodying the present inventive concept and well adapted to perform the present improved method; and

Figure 2 is a plan view of the same, as it would appear in an advanced stage of its operation.

In order to illustrate a practical reduction to practice of this inventive concept, inclusive of typical means for performing the improved method, the accompanying drawing is presented herewith and will be described in detail. No limitation of this invention is intended to be expressed or implied by this example given. The scope of the inventive concept is to be measured by the appended claims.

10 In the drawing, reference character 5 denotes a hollow built-up metallic base, upon which is mounted a motor 6 having a V-faced milling cutter 7 which preferably is rotated in a clockwise direction as viewed in Figure 1.

15 Another motor 8 is mounted upon the base 5 and spaced away from the motor 6. The second motor 8 has a milling cutter 9 that is adapted to gage-cut the exterior surface of a detachable drill bit or the like, that is positioned and held adjacent thereto.

20 The base 5 has a lateral projection 5a, upon which is rotatably journaled a mechanism for holding and presenting detachable rock bits or the like, to the milling cutter 7 and then to the gage-cutter 9 in a brief, continuous operation while said bit is hot.

25 The mechanism for holding and presenting hot detachable bits to the milling cutter for sharpening and then to the gage-cutter, preferably is built up as follows:

30 A spindle 10 is slidably mounted in a water jacketed sleeve 12 having means 13 for circulating water therethrough, from any convenient source not shown. A bit holder 14 is rotatably positioned through the spindle 10 and is shaped at one end to receive the socket of a detachable rock drill bit or the like, designated at 15. The opposite end of the holder 14 is provided with an indexing star 16 which is positioned and adapted to contact a pawl 17 mounted on the base 5, when the bit holder is moved, as will be more fully set forth.

35 The spindle 10, together with the water jacketed sleeve 12 and the bit holder 14, are carried upon an arm 18 which in turn is attached to a hollow shaft 19 journaled in bearings 20 for limited rotary movement by means of a handle 21 affixed thereto.

40 Extending through the hollow shaft 19 is a solid shaft 22 that is rotatable with reference to said hollow shaft 19 by means of a ratchet assembly 23 selectively operable by a handle 24. The ratchet assembly 23—24 is adapted to rotate the solid shaft 22 in stages of a relatively few degrees to any one of a number of predetermined positions. At the end of shaft 22 that is opposite the ratchet 23, an eccentric 25 is affixed thereto. A connecting link 26 pivotally joins the spindle 10, by means of a lug 10a thereon, to the eccentric 25 so that by angular

or rotary movement of the shaft 22, the spindle 10 is caused to move longitudinally in predetermined increments.

When the hollow shaft 19 is rotated toward the milling cutter 7, the detachable bit 15 positioned on the bit holder 14 may be presented to said milling cutter for removing metal therefrom to sharpen the cutting edges thereof. Bosses 27 on the sleeve 12 are positioned and adapted to contact a pair of stops 28 positioned on the base element 5 to thereby limit the angular movement of the mechanism toward milling cutter 7. Rotation of the shaft 22 will longitudinally advance or retract the spindle 10 and the bit holder 14, with the result that the detachable bit 15 may be presented properly to the milling cutter 7.

If the milling cutter 7 runs clockwise, as viewed in Figure 1, i. e., from the center toward the outside edge of the bit 15, in the position illustrated, the hot metal of the bit will tend to be dragged or "upset" outwardly as the cutting edges thereof are sharpened. This action tends to maintain the gage of the bit, which otherwise would tend to be lost, as hereinabove explained.

However, the bit 15 may be presented to the milling cutter 7 adjacent the lower part of the periphery thereof, in which position the milling action will be reversed with reference to the bit, in that the milling cutter will move toward the center of the bit. This will effect an equally satisfactory sharpening of the bit although the outward upsetting tendency will be lacking.

Usually, there are four radial chisel-like cutting edges on each detachable bit. Therefore, to sharpen a bit such as shown at 15, the said bit must be presented to the sharpening cutter 7 in four positions so that said cutter may operate in each V-shaped space between the cutting edges. To rotate the hot bit 15 so as to present it in four positions to the milling cutter 7, the bit holding assembly as hereinabove set forth, is moved away from the milling cutter 7, by means of the handle 21, sufficiently to bring the indexing star 16 in contact with the pawl 17 thereby to rotate the bit holder 14 and the bit 15 about 90°. This indexing operation is repeated until all of the cutting edges of the bit have been properly milled to sharp edges.

After the cutting edges of the bit 15 have been sharpened as above set forth, the next operation is to gage-cut the bit. The method and apparatus for positioning and gage-cutting the hot bit in the same continuous operation, will next be set forth. An arm 29 is journaled for free arcuate movement upon the hollow shaft 19 adjacent one of the bearings 20. If desired, a counterweight 30 may be affixed to the arm 29 to counterbalance the weight of said arm and thereby to reduce the amount of force required to move it about its axis of limited rotation.

As illustrated in Figure 1, the angularly movable arm 29 is held in a predetermined position by means of a stationary cam 31 on one of the bearings 20, engaging a follower 32 carried upon a slide 33 that is urged toward the cam by means of a spring 34 bearing against a bracket 35 affixed to the arm 29 and bearing against a collar 36 affixed to a rod 37 attached to the slide 33 and guided by means of said bracket 35 and another similar bracket 38 also attached to the arm 29.

The slide 33 and its associated mechanism are movable along and with reference to the arm 29. The slide 33 carries a hand wheel 39 which

is adapted to rotate a bit-driving head 40 through the intermediary of suitable gearing, shown in dotted lines at 41.

When the bit holder assembly is moved away from the milling cutter 7 by means of the handle 21 toward the arm 29, the sleeve 12 comes in contact with a contact member 42 affixed to the arm 29, whereupon said arm 29 and its associated mechanism begin to move angularly and conjointly with the bit holder assembly. The force for such further angular movement is supplied manually through the intermediary of the handle 21 and is sufficient to force the cam-follower 32 out of its retaining notch in the cam 31, and as the entire assembly continues to move arcuately, downwardly and to the right as viewed in Figure 1, the cam-follower 32 will permit the slide 33 and, therefore, the bit driver 40 to slide or move inwardly toward the bit 15 so that said driving head 40 will engage the points or cutting edges or the grooves therebetween, of the bit 15 as clearly illustrated in Figure 2. As a part of contact member 42, a more positive latch between the arm 29 and the bit holder assembly may be provided and controlled by movements of the cam follower 32. If desired, an operator may begin turning hand wheel 39 to rotate driving head 40 to facilitate the engagement of said driving head 40 with the bit 15 as they conjointly move downwardly about their general and common pivotal axis.

A stop member 43 is positioned upon the base 5 to stop the downward arcuate movement of the arm 29 in a position to present the detachable bit 15 to the gage-cutter 9 which is driven by the motor 8. Rotation of the hand wheel 39 will drive or turn the bit 15 to present all sides thereof to the gage-cutter 9.

After the gage-cutting has been completed, the handle 21 is rotated counter-clockwise as shown in the illustrations, to restore the arm 29 and its associated mechanism to the position illustrated in Figure 1 where it is automatically held until the next bit is to be sharpened. The upper movement of the arm 29 and its associated mechanism causes the slide 33 to move away from the bit 15 as the follower 32 moves along the cam 31, thus to release the engagement of the driving head 40 from the bit 15.

If a further latching engagement is provided between the arm 29 and the bit-holding assembly, then such engagement would also be released by movement of the cam follower 32, whereupon the bit 15 having been sharpened and cut to gage, may be removed. As above stated, the sharpening milling cutter 7 may be rotated in either direction, but it is usually preferable to turn this milling cutter from the center toward the outer edge of the bit to upset the hot metal of the bit outwardly and thus maintain its cutting diameter or gage.

As clearly illustrated in Figure 1, it appears preferable to provide raised portions 5b and 5c on the hollow base 5, upon which to mount the motors 6 and 8. This arrangement provides a lower central area on the base 5, above which the bit holding mechanism operates. Immediately below the milling cutter 7 is a duct 44 and immediately below the milling cutter 9 is another duct 45. These ducts are open at their tops and connected with the hollow interior of the base 5 so that cuttings and fumes from the bits being sharpened will be drawn downwardly therethrough into the hollow base 5.

An exhaust fan 46 that may be driven by any

suitable means, such as an electric motor not shown, is connected at 47 with the hollow interior of the base 5 adjacent the bottom thereof. Fumes are thus drawn from the interior of the base and away from the operator. The hot chips or cuttings from the bits are thrown downwardly into pans 48. The cuttings are directed into the pans by means of a plurality of inclined baffles 49, which feature is of importance because the hot chips from the bits tend to form a hard slag, and unless they definitely are directed into the pans 48, they would tend to cake upon the bottom of the base 5 and might cement the pans 48 thereto. The pans 48 normally are removable from the base, access thereto being had through doors 50.

In order to position the motor 8 which drives the gage-cutting miller 9, in proper relationship to the bit 15 for cutting it to gage, a plurality of adjustments are provided for said motor. A plate 51 is movable transversely of the axis of the bit 15 along rails 52 by means of a hand wheel 53 operating a thrust screw 54. Another plate 55 is superposed upon the plate 51 and is movable parallel to the axis of the bit 15 by means of a hand wheel 56. Another plate 57 is mounted upon the plate 55 and is angularly movable to adjust the angle of the gage-cutting miller 9 with reference to the bit 15 by means of a hand wheel 58. The motor 8 is carried upon the plate 57 and therefore is subject to all of the above enumerated adjustments.

Briefly, the present method consists in supporting a red hot bit, presenting it to a sharpening milling cutter while so heated, thus subjecting it to a combined upsetting and sharpening action, automatically rotating the bit to present all faces thereof to the sharpening cutter, then positioning the bit for contact with a gaging miller and rotating the bit in cutting proximity to said gaging-cutter all in one prompt, continuous operation.

The mechanism herein illustrated and described in detail for performing the present improved method, is well suited for this purpose, but is by no means the only machine capable of performing the method. This method could be performed in numerous other ways with the aid of different mechanisms.

While this specification discloses preferred means for reducing the present invention to practice and a preferred embodiment of the invention, changes may occur to those skilled in the art and may be made within the scope of the appended claims, without departing from this inventive concept.

What we claim and desire to secure by Letters Patent is:

1. A device of the character disclosed comprising means for sharpening a bit, means for gaging a bit spaced away from said sharpening means, a bit holder pivotally mounted adjacent said sharpening and gaging means and angularly movable toward and away from each, a bit-driving head automatically engageable with a bit on the holder by angular movement of said holder toward said gaging means, and mechanism for rotating said driving head for gaging the bit.

2. A device of the character disclosed comprising means for sharpening a bit, means for gaging a bit spaced away from said sharpening means, a bit holder pivotally mounted adjacent said sharpening and gaging means and angularly movable toward and away from each, indexing

mechanism positioned to contact and to rotate the holder when said holder is angularly moved, a rotary bit-driving head automatically engageable with a bit on the holder by angular movement of said holder toward said gaging means, and mechanism for rotating said driving head for gaging the bit.

3. A device of the character disclosed comprising means for sharpening a bit, means for gaging a bit spaced away from said sharpening means, a bit holder pivotally mounted adjacent said sharpening and gaging means and angularly movable toward and away from each, means inclusive of a rotatable eccentric at the pivotal mounting for said holder and a link connecting said eccentric with said holder for extending the effective radial length of the holder, a bit-driving head automatically engageable with a bit on the holder by angular movement of said holder toward said gaging means, and mechanism for rotating said driving head for gaging the bit.

4. A device of the character disclosed comprising means for sharpening a bit, means for gaging a bit spaced away from said sharpening means, a bit holder pivotally mounted intermediate said sharpening means and said gaging means and angularly movable toward and away from each, means for circulating a fluid coolant in heat-exchange proximity to the holder, a rotary bit-driving head automatically engageable with a bit on the holder by movement of said holder toward said gaging means, and mechanism for rotating said driving head for gaging the bit.

5. A machine for reconditioning detachable rock drill bits or the like comprising means for sharpening a bit, means for gaging a bit spaced away from said sharpening means, a bit holder pivotally mounted intermediate said sharpening means and said gaging means and angularly movable toward and away from each, a rotary bit-driving head coaxially mounted for selective conjoint angular movement with said holder and radially slidably theretoward, mechanism inclusive of a stationary cam adjacent said axis of angular movement and a cam follower engaging said bit-driving head for automatically engaging said driving head with a bit on the holder when said holder is angularly moved toward said gaging means, and mechanism for rotating said driving head for gaging a bit engaged thereby on the holder.

6. A machine for reconditioning detachable rock drill bits or the like comprising means for sharpening a bit, means for gaging a bit spaced away from said sharpening means, a bit holder pivotally mounted intermediate said sharpening means and said gaging means and angularly movable toward and away from each, a rotary bit-driving head coaxially mounted for selective conjoint angular movement with said holder and radially slidably and spring-urged theretoward, mechanism inclusive of a stationary cam adjacent said axis of angular movement and a cam follower engaging said bit-driving head for automatically engaging said driving head with a bit on the holder when said holder is angularly moved toward said gaging means, mechanism for rotating said driving head for gaging a bit engaged thereby on the holder, and means for extending the effective radial length of said bit holder in predetermined increments.
